(57) **CLAIM**

The ornamental design for a light fixture, as shown and described.

DESCRIPTION

FIG. 1 is a bottom front perspective view of the light fixture showing my new design;

FIG. 2 is a top front perspective view of the light fixture showing my new design;

FIG. 3 a front elevational view thereof, the rear elevational view being a mirror image;

FIG. 4 is a left side elevational view thereof, the right side elevational view being a mirror image;

FIG. 5 is a bottom plan view thereof; and,

FIG. 6 is a top plan view thereof.

The broken lines shown in the drawings are included for the purpose of illustrating portions of the article that form no part of the claimed design.
